CATCH

Earl M. Borchers, Rockford, Ill., assignor to American Cabinet Hardware Corporation, Rockford, Illinois, Rockford, Ill., a corporation of Illinois

Application November 10, 1944, Serial No. 562,766

6 Claims. (Cl. 292—18)

1

The invention pertains to catches of the type intended for use in releasably holding cabinet doors and the like in closed position; and the primary object of the invention is to provide a catch which is capable of quick and easy installation or removal.

Another object is to provide a catch of the character aforesaid which is releasably held in position by means of resilient retaining elements.

A general object is to provide a catch embodying the aforesaid advantageous features which may be manufactured economically and which is exceptionally durable.

The objects of the invention thus generally stated, together with other and ancillary advantages, are attained by the construction and arrangement shown by way of illustration in the accompanying drawings forming a part hereof, in which:

Fig. 1 is a perspective view of my improved catch shown in relation to a mounting plate apertured to receive the catch.

Fig. 2 is a fragmentary horizontal sectional view showing the catch applied to a double pan door in operative relation to a strike on an associated door frame.

Fig. 3 is a front view of the catch.

Fig. 4 is a similar view showing the catch in relation to a mounting plate.

Fig. 5 is a fragmentary perspective view of the catch installed in its mounting plate, the view being taken from the rear side of the plate.

Fig. 6 is a view similar to Fig. 2 but illustrating an equalizing action of the strike engaging jaws when the catch and its strike are not accurately alined, the jaws being shown in section.

Fig. 7 is a fragmentary vertical sectional view illustrating the application of the catch to a wooden door.

In the present preferred embodiment of the invention, the catch comprises generally a U-shaped frame 8 having spaced parallel side plates 9 and 9' and a front plate 10 integral with the side plates. Within such frame is a pair of strike-engaging jaws 11 pivotally mounted upon a pivot pin 12 extending between and fastened at opposite ends in the side plates 9 and 9'. Mounted on the pin 12 is a torsion spring 13 urging the jaws 11 into position to receive and yieldably retain a strike 14, the front plate 10 of the frame having a hole 15 for the passage of the strike.

Since the catch is especially designed for mounting in double pan doors, the inner pan of

2

the door D will in most instances constitute the mounting plate. As shown in Fig. 1, the inner pan 16 is formed with a square hole 17 dimensioned to receive the frame 8 and more particularly the side plates 9 and 9' thereof. Thus the length of the hole corresponds to the width of the side plates of the frame and the width of the hole corresponds to the lateral spacing of the side plates. To provide abutment means for limiting movement of the frame through the hole 17, the front plate is elongated to form end portions bearing against the outer face of the mounting plate at opposite side edges of the hole.

For the purpose of disengageably retaining the catch in its mounting plate the side plates 9 and 9' are formed with a plurality of resilient detent elements so constructed and arranged as to engage with the mounting plate at the edges of the hole 17 therein when the front plate is forced flat against the outer face of the mounting plate. Such resilient detent elements are in the present preferred embodiment of the invention comprised of two pairs of fingers 18, 18' and 19, 19', one pair constituting a positive stop means for coaction with the extended ends of the front plate to positively hold the catch against movement transversely of the opening, and the other pair frictionally engaging with the edges of the hole 17 to assist in retaining the catch in position and hold it against shifting laterally relative to the mounting plate.

The positive detent elements or fingers 18, 18' are respectively formed on the side plates 9 and 9' and in general at diagonally opposite corners of the frame. In forming the fingers 18 and 18', the side plates 9 and 9' are formed with slots 18a shown clearly in Fig. 1 and the fingers bent somewhat outwardly. The extreme forward ends of the fingers are disposed in a vertical plane spaced rearwardly from the front face of the plate 10 a distance corresponding to the thickness of the mounting plate, and these ends being offset form abutments for engaging with the inner face of the mounting plate at the edge of the opening 17, thereby positively holding the catch against removal. It will be seen that in bending the fingers outwardly cam surfaces are formed which engage with the edges of the opening in the mounting plate and force the fingers inwardly as the catch is thrust home.

Like the fingers 18 and 18', the frictional detent elements or fingers 19 and 19' are respectively made integral with the plates 9 and 9' and located at the other corners of the supporting

frame. As shown clearly in Fig. 5 these fingers terminate at their forward ends immediately rearward of the front plate 10 substantially in the plane of the rear face thereof, and being bent laterally outward from the side plates their outer sides provide frictional gripping surfaces for engagement with the edges of the hole 17. It will be seen that while the fingers 18 and 18' positively lock the catch against movement in a front to rear direction, the fingers 19 and 19' hold the supporting frame against lateral shifting movements.

The strike engaging jaws 11 have their rear end portions constructed to provide yokes 20 and 20' pivotally mounted in nested relation upon the pin 12. Each of the jaws is made from sheet metal and comprises an arm 21 formed with ears 22 integral with opposite side edges of the arm and apertured to receive the pivot pin 12. Forwardly of the ears 22 the arms are suitably shaped to form opposite jaw portions 23 which are urged toward each other by the torsion spring 13, the latter being coiled about the pivot pin 12 and having opposite end portions 24 engaging the rear ends of the jaw arms 21. To limit the approaching movement of the jaw portions 23, bosses 25 and 25' are struck up from the inner sides of the plates 9 and 9' for engagement with stop lugs 26 and 26' on the respective jaws, each of said lugs being formed integral with one of the ears 22 (Fig. 2).

The strike 14 is herein shown as comprising a pin suitably fastened to the frame member 27 of the cabinet C. The projecting end of the pin has a head 28 providing a tapering shoulder for engagement by the jaws of the catch. Preferably the strike is proportioned so that when received between the jaws, the stop lugs 26 and 26' are held away from their respective bosses 25 and 25' (Fig. 2) so that the jaws are free to move in unison for a limited distance to one side or the other of the supporting frame. Thus, if the strike should not when installed be aligned exactly with the catch, both jaws will nevertheless operate with an equalizing action to exert a gripping force on the strike (Fig. 6).

While the improved catch is especially designed for mounting in metallic cabinet doors of the double pan type so as to be concealed substantially from view and present no undesirable obstruction upon the inner face of the door, it will be understood that the reverse arrangement may be employed and the catch mounted upon the cabinet frame with the strike upon the door. Also, the catch is applicable to door or frame members of wood as illustrated in Fig. 7. In such event, a separate mounting plate 16a may be fastened to the door or other support in overlying relation to a recess 28, the frame of the catch being inserted through an opening in the plate 16a, and retained in such opening in the manner above set forth.

Removal of the catch from its mounting plate may be readily accomplished by means of a pointed instrument inserted through the hole 15 in the front plate 10 and into engagement with the positive locking fingers 18 and 18'. By exerting a force upon the tool in the nature of a prying action, the locking fingers may be disengaged one at a time from behind the mounting plate and the catch removed. The manner in which the tool T may be inserted for this operation is illustrated in Fig. 4.

It will be seen that I have provided a catch which is simple in construction and therefore susceptible of economical manufacture. But the

feature of special importance is the ease with which the catch may be installed, since the catch may be securely fastened in position simply by pressing the frame through a hole in the mounting plate dimensioned to correspond with the cross sectional shape of the frame at a point rearwardly of the front plate. Through the use of both positive and frictional detent elements, the catch is held firmly not only against movement in a front to rear direction but also against lateral shifting movement. When it is desired to remove the catch from its supporting plate, the positive elements may be easily pried out of holding relation to the edge of the opening.

I claim as my invention:

1. A catch having a supporting frame comprising a side plate and a front plate for limiting movement of the side plate through a mounting member having a hole therein proportioned to conform substantially to the width of said plate, an elongated spring finger on said side plate movable into positive holding engagement with the mounting plate automatically as an incident to the forcing of the frame into its said limit position, and a second spring finger of a length somewhat greater than the length of the first mentioned finger so as to be frictionally engageable with the edge of the hole and mounting plate.
2. A door catch comprising a U-shaped frame having spaced parallel side plates and an apertured front plate integral with the side plates and extending beyond the edges thereof, strike-engaging jaws pivotally supported in said frame, and means for releasably retaining said frame in a mounting plate having an opening dimensioned to receive the side plates of the frame, said means comprising a pair of spring fingers formed integral with each of the side plates, one having its free end offset from the plane of the side plate and spaced from the front plate a distance corresponding to the thickness of the mounting plate and adapted to engage with the inner face thereof in opposed relation to the front plate, the other one of said fingers projecting into the plane of the front plate and adapted to engage frictionally the side edge of the opening in the mounting plate.
3. A door catch comprising a U-shaped frame having laterally spaced side plates and an apertured front plate integral with the side plates and extending beyond the edges thereof, strike-engaging jaws pivotally supported in said frame, and means for releasably retaining said frame in a mounting plate having an opening dimensioned to receive the side plates of the frame, said means comprising a pair of spring fingers formed integral with each of the side plates, one having its free end offset from the plane of the side plate and spaced from the front plate a distance corresponding to the thickness of the mounting plate and adapted to engage with the inner side thereof in opposed relation to the front plate, the other one of said fingers projecting into the plane of the front plate and adapted to engage frictionally the side edge of the opening in the mounting plate, the fingers of each pair being respectively disposed at diagonally opposite corners of said frame.
4. A catch having a supporting frame comprising a pair of side plates with means at one end thereof for limiting movement of the frame through a mounting member having a hole therein of a size conforming substantially to the cross sectional shape of the frame, and means on said side plates movable into positive holding engagement with the mounting plate automatically as an inci-

dent to the forcing of the frame into its said limit position whereby to prevent reverse withdrawal of the frame from the said hole in the mounting plate, and other means on said frame yieldably held in frictional engagement with the hole in the mounting plate at least at one edge thereof to restrain lateral shifting movement of the frame relative to the mounting plate.

5. A catch comprising, in combination, a supporting frame having a pair of laterally spaced side plates and a front plate connecting said side plates, said frame being adapted to be assembled with a mounting plate having a hole therein dimensioned to correspond substantially to the cross sectional shape of the frame rearwardly of the front plate, and the front plate having portions engaging with the mounting plate to limit movement of the frame in one direction relative to said hole, and a plurality of spring fingers forced outwardly from the side plates so as to snap into position behind the mounting plate when the front plate is forced into position against the mounting plate, strike-engaging jaws pivotally mounted between said side plates, said front plate being apertured for the passage of a strike and the forward ends of said jaws terminating in spaced relation to the front plate so as to permit the insertion of a tool through the opening in the front plate and into engagement with said finger.

6. A catch comprising, in combination, a supporting frame having a side plate and a front plate, said catch being adapted to be installed in a mounting plate having a hole therein dimensioned to receive the side plate rearwardly of the front plate, and the front plate having portions engaging with the mounting plate to limit movement of the frame in one direction, and a spring finger forced outwardly from the side plate so as to snap into position behind the mounting plate when the front plate is forced into position against the mounting plate, strike-engaging jaws pivotally mounted between said side plates, said side plate having a slot at one side of the finger and said front plate being apertured for the passage of a strike and to permit the insertion of a tool into said slot for engagement with said finger.
